[57] ABSTRACT

A step-in safety ski heel binding includes a heel holding means engaging the heel of a ski boot, the heel holding means operatively connected to a linkage or lever arrangement which engages one or more flat or leaf springs. The force of the springs acting against the lever arrangement retains the heel of the ski boot on the ski and absorbs ordinary skiing shocks without release and releases the ski boot when an upwardly directed force is exerted on the heel-holding means which exceeds the force of the springs.

FIG. 1

FIG. 2

FIG. 3

SAFETY STEP-IN HEEL BINDING FOR SKIS

BACKGROUND OF THE INVENTION

1. Field of the Invention

This invention relates to a step-in-safety ski heel binding employing one or more flat or leaf springs in the construction thereof.

2. Prior Art Relating to the Disclosure

Numerous step-in safety ski heel bindings are known which employ one or more coil springs in conjunction with a toggle arrangement to retain a ski boot on a ski and to release the boot when an abnormal force is exerted by the ski boot on the ski heel binding. Patents which disclose ski heel bindings of the type above mentioned include U.S. Pat. Nos. 3,123,349; 3,291,500; 3,497,230; 3,529,834; 3,529,846 and 3,554,572. Such bindings are expensive to manufacture because of the labor necessary to fabricate them. In addition, numerous parts are required for the binding.

There is and has been a need for a ski binding which is inexpensive to buy, reliable over a reasonable period of time, simple in construction and, therefore, easy to use and maintain.

SUMMARY OF THE INVENTION

The step-in ski binding of this invention includes a heel holding means engaging a ski boot heel, the heel holding means operatively connected to a linkage or lever arrangement operating against one or more flat or leaf springs to absorb ordinary ski shocks and to release the skier in the event of a fall or exertion of abnormal pressure by the ski boot against the heel retaining means. The step-in safety heel binding provides a binding which (1) releases a skier dependably when necessary, (2) absorbs ordinary ski shocks without unnecessary release, (3) is easy to adjust, use and maintain, and (4) is less expensive than bindings employing one or more coil springs.

BRIEF DESCRIPTION OF THE DRAWINGS

FIG. 1 is a perspective view of the ski heel binding of this invention.

FIG. 2 is a side elevational view of the ski heel binding of this invention with the ski boot held in place by the binding in position for skiing; and

FIG. 3 shows a similar view of the binding of FIG. 1 except in the fully released position wherein it is pivoted upwardly and the binding is released from the ski.

DESCRIPTION OF THE PREFERRED EMBODIMENTS

FIG. 2 shows a heel portion of a ski boot 10 secured to a ski 11 by a toe-holding device (not shown) and a heel binding 12. The heel binding comprises an elongated base 13 secured by screws 15 to the upper surface of a ski 11. The screws may be extended through a serrated slot (not shown) along a portion of the length of the base 13 to adjust the base relative to the length of the ski boot. The base 13 has upwardly extending side walls 16 which support a pivot pin 17 extending essentially parallel to and transverse to the ski 11. Extending upwardly from and attached by rivets 14 or other means to the rear end of base plate 13 are one or more flat or leaf springs 18 and 19. Leaf spring 19

may be termed the "release" spring and may be formed integral with or separately from the base 13. Spring 18 may be termed a "shock absorbing" spring and is mounted forwardly of spring 19. Spring 18 has a V-shaped configuration, the base of the "V" denoted by reference numeral 18a. Shock absorbing spring 18 acts to absorb shocks encountered during ordinary skiing without releasing the ski boot from the ski.

An adjustment screw 20 is threaded through holes in the upper end of release spring 19. The distance between the end of adjustment screw 20 and the rear surface of spring 18 determines the release force necessary to release the ski boot from the binding. Preferably, the upper portion of release spring 19 is formed into an upsidedown U-configuration and the adjustment screw 20 threaded through both of the legs of the U. The legs of the "U" are spread slightly so that there will be tension on the adjustment screw 20 to keep it from vibrating loose during skiing. The travel of the screw should be limited to prevent the binding from being adjusted too tightly to release.

A lever 21 is mounted for pivoting about pivot pin 17. The forward end of lever 21 is provided with a heel supporting plate 22 while the rear portion 23 thereof presses or acts against the shock absorbing spring 18.

Heel depressing lever 24 is also mounted for pivoting about pivot pin 17. The forward end of lever 24 is provided with a heel engaging plate 25. The plate 25 may be formed into a flat spring so as to exert forward pressure on the ski boot heel independently of the leaf springs 18 and 19. The rear end of lever 24 turns downwardly and is provided with a slot 26 through which lever 21 extends so that an upwardly directed force F on the heel engaging plate 25 is transmitted through the lever 24 as a downwardly directed force on the rear portion of lever 21. The terminating edge of lever 21, in turn, acts against spring 18 to press it backwardly against the nub end of adjustment screw 20 which in turn acts against spring 19.

The heel engaging plate 25 is adjustable by a screw 27 threaded through levers 21 and 24 to different elevations above the heel supporting plate 22. A spring 31 is inserted between the levers 21 and 24 surrounding the screw 27. The lever 24 may also be provided with integrally formed downwardly extending flaps 28 to prevent snow and ice from caking in the interior of the mechanism. A recess 29 may be provided on the upper end of spring 18 to receive a ski pole tip allowing the skier to push against the spring to aid in stepping out of the binding when desired. Rings 30 may also be secured to the upper surface of lever 24 for attachment of a runaway strap.

OPERATION

To insert a ski boot into the ski binding of this invention, the heel of the boot is pressed down against the heel supporting plate 22 which causes it to pivot downwardly about pivot pin 17 to the position shown in FIG. 3. The terminating end 23 of lever 21, at the same time, pivots upwardly and acts against leaf spring and release spring 19. In the position illustrated by FIG. 1 forward pressure is exerted against the heel of the boot by the flat spring formed as an integral part of the heel depressing means 25. This forward pressure operates independently of the release and shock absorbing springs 18 and 19.

If the skier wants to release the heel binding from the boot at any time, pressure by means of a ski pole tip or other suitable means may be exerted against springs 18 or 19, allowing the rear portion 23 of lever 21 to pivot downwardly past the apex 18a of spring 18.

During skiing or due to a fall of the skier, an upwardly directed force F is transmitted from the heel of the ski boot to lever 24 in contact with the heel, tending to cause the forward end of lever 24 to pivot upwardly about pivot pin 17 and to press against the lower surface of the head of screw 27. The screw may be positioned on either side of the pivot pin 17. The rear end of lever 24 exerts a downwardly directed force on lever 21 where it contacts lever 24. Lever 21, in turn, acts against the forwardly directed force of spring 18 and 19 and forces spring 18 rearwardly into contact with the tip of adjustment screw 20 which reacts against the release spring 19. If the upwardly directed force F exceeds the combined forces of springs 18 and 19, lever 21 is forced past apex 18a of spring 18 to release the heel of the ski boot. The force necessary to release the ski boot from the heel binding may be controlled by the degree to which the release spring 19 is bent. The less the spring is bent, the less is the release force at the time of release. The size of the shock and release springs and the material of which they are made can also be varied to control the release force.

The step-in ski heel binding described can be fabricated from a minimum number of parts. Leaf or flat springs employed may be stamped from any suitable metal and do not require tempering as do coil springs used by prior ski heel bindings. Most of the remaining portions of the binding can also be made by a stamping operation which is one of the least expensive manufacturing methods.

The embodiments of the invention in which a particular property or privilege is claimed are defined as follows:

1. A step-in ski heel binding operable to automatically release a ski boot from a ski on exertion of an abnormal force on the binding comprising:

a base having parallel upwardly extending side walls, a pivot pin supported by and extending in a transverse direction between the side walls, linkage means secured to the pivot pin intermediate its ends for vertical movement about the pivot pin, one end of the linkage means engaging the heel portion of the ski boot, leaf spring means including a first leaf spring secured to the base and extending upwardly to engage the opposite end

2. The binding of claim 1 wherein the second lever forms a housing surrounding the first lever to prevent caking of snow and ice in the interior of the binding.

3. The binding of claim 1 including means on the upper end of the first leaf spring for receiving the tip of a ski pole to exert sufficient pressure against the spring to release the binding from the boot.

4. The binding of claim 1 wherein the linkage means includes (1) a first lever mounted for pivoting about the pivot pin in a vertical direction having a forward end portion engaging the bottom surface of the heel of a ski boot, (2) a second lever pivotally mounted about the pivot pin for pivoting in a vertical direction having a forward end portion engaging the top rim of the heel of a ski boot and a rear portion turned downwardly and provided with a slot through which the rear portion of the first lever extends so that, in the presence of an upwardly directed release force by the heel of the ski boot against the forward end portion of the second lever, a downwardly directed release force is transmitted to the rear portion of the first lever against the pressure of the leaf spring means.

5. A step-in safety ski heel binding operable to automatically release on exertion of an upwardly directed release force exceeding the force of adjustable leaf spring means, comprising:

a base for securing the binding to a ski having upwardly extending sidewalls parallel to the length dimension of the base,

a pivot pin supported by and extending between the sidewalls of the base transverse to the length dimension of the base,

a first lever mounted on the pin intermediate its ends for vertical movement about the pin between a skiing position and a release position, the forward end of the first lever including means contacting the bottom surface of the heel of a ski boot,

leaf spring means including a first leaf spring secured to the rear portion of the base extending upwardly to contact the rear end of the first lever, the spring means normally retaining the first lever in the skiing position in the absence of a release force, and

a second lever mounted on the pin intermediate its ends for vertical movement about the pin between the skiing position and the release position, the forward end of the second lever including means engaging the top rim of the heel of the ski boot and the rear end having a downwardly extending flange provided with a slot through which the rear end of the first lever extends so that an upwardly directed release force against the forward end of the second lever by the ski boot is transmitted as a downward force against the first lever and against the leaf spring means to progressively deflect the leaf spring means until the upwardly directed release force exceeds the force of the leaf spring means, whereupon the first and second levers move to release position releasing the ski boot from the ski.

6. The binding of claim 5 including a second leaf spring extending upwardly back of the first leaf spring and adjustable means extending between the two leaf springs for adjusting the release force necessary to overcome the combined force of the forward and rear springs.
